UNITED STATES PATENT OFFICE.

NICHOLAS STIREN, OF LITCHFIELD, MINNESOTA.

COMBINATION WRENCH AND THREAD-CUTTER.

No. 914,199.

Specification of Letters Patent. Patented March 2, 1909.

Application filed June 11, 1908. Serial No. 437,814.

To all whom it may concern:

Be it known that I, NICHOLAS STIREN, a citizen of the United States, residing at Litchfield, in the county of Meeker and State of Minnesota, have invented certain new and useful Improvements in a Combination Wrench and Thread-Cutter, of which the following is a specification, reference being had to the accompanying drawings.

10 My invention relates to improvements in wrenches and particularly to improvements in combination-wrenches adapted to be used for a variety of purposes.

An object of my invention is to provide a 15 combination-tool of the class described which will be simple in construction, comparatively cheap in manufacture and most efficient in operation and which will have a wide field of usefulness.

20 In the drawings illustrating the principle of my invention and the best mode now known to me of applying that principle, Figure 1 is a side elevation, partly in section, showing my new wrench; Fig. 2 is a side elevation showing the opposite side from that shown in Fig. 1, one of the wrench members being shown moved out from the end of the shank; Fig. 3 shows the wrench members removed and the screwdriver in place; Fig. 4 25 shows one of the wrench members adjusted to allow the thread-cutting dies to be moved apart; Fig. 5 shows the shank member fitted with a reamer; Fig. 6 is a detail of the screwdriver; Fig. 7 is a detail of the reamer; Fig. 8 30 is a detail of a tap which may be used with my new combination tool; and Fig. 9 is a detail of a thread-cutting die.

The body portion or shank *a* is provided at its ends with threaded holes *b*, *c*. In the 40 hole *b*, screws the threaded shank *d* of the wrench-head *e* formed with jaws *f* and *g*. The wrench-head *e* is also formed with a hammer-head *h*. The hole *c* is threaded and communicates with a recess *i* in which is slidably fitted the two-part thread-cutting die *j* shown in detail in Fig. 9. The bottom wall of the recess *i* is formed with a hole *k* (Figs. 2 and 3), through which may be passed the rod or pipe upon which is to be cut the

threads by the die *j*. The threaded shank 50 *m* screws into the hole *c*; and the free end of this shank *m* projects into the recess *i* and is adapted to press against one side of the thread-cutting die *j* and thereby to clamp the latter firmly in place upon the pipe or rod to be threaded. By turning the wrench head *n*, as is shown in Fig. 4, the parts of the die *j* may be made free to be adjusted relatively to each other.

In the middle of the shank *a* is formed a 60 hole *o* in which may be fitted the squared head of a reamer *p* or a tap *q*. The wrench-head *e* may be removed and the threaded shank of a screwdriver *r* may be fitted in the threaded hole *b*. It will be obvious that the 65 wrench head *e* may be screwed into the hole *c* and the wrench head *n* into the hole *b*, so that these wrench heads are interchangeable so far as position is concerned. Further, by turning either wrench head upon its threaded post as an axis, the jaws *f*, *g* will be moved towards or away from the shank member *a*, thereby varying the leverage of the jaws. Again, by turning either wrench head upon 70 its threaded posts *d*, *m*, as an axis, the shoulder *s* will be moved away from the opposed end of the shank member, leaving a space 75 in which may be engaged a nut *t* (Fig. 2).

I claim:

A combination tool of the character described, consisting of a shank member formed with a recess, the walls of which hold a thread-cutting device, and formed also with a threaded hole which communicates with said recess and in which is inserted a threaded post, the inner end of which projects into said recess and bears against said device to clamp the same in place and which carries a wrench-head formed with a pair of jaws. 80

In witness whereof I have hereunto set my 90 hand at said Litchfield this 6th day of June, A. D., 1908, in the presence of the two undersigned witnesses.

NICHOLAS STIREN.

Witnesses:

E. P. PETERSON,
HARRY EKBLAD.
